(57) **CLAIM**

The ornamental design for a medical protective shield with surface pattern, as shown and described.

DESCRIPTION

FIG. 1 is a top elevational perspective view the medical protective shield with surface pattern comprising our new design;

FIG. 2 is an enlarged top elevational perspective view of a portion thereof;

FIG. 3 is a bottom view thereof;

FIG. 4 is a top view thereof;

FIG. 5 is a left side view thereof;

FIG. 6 is a right side view thereof;

FIG. 7 is a front view thereof; and,

FIG. 8 is a back view thereof.

The broken lines shown in the drawings illustrate portions of the medical protective shield with surface pattern that form no part of the claimed design. The phantom dash-dot lines in the drawings represent the boundary of the claimed design, and also form no part of the claimed design.

1 Claim, 6 Drawing Sheets
